UNITED STATES PATENT OFFICE.

HARRY H. HISTAND, OF DOYLESTOWN, PENNSYLVANIA.

PROTRACTOR.

Application filed April 10, 1924. Serial No. 705,584.

My invention relates to protractors adapted to be used on a drawing board in place of triangles. The protractor consists of two arms or blades which may be set at any suitable angle with relation to each other from zero to ninety degrees and carries three different scales for this purpose. Beside the ordinary scale reading up to ninety degrees, it carries a second scale divided into eighths of forty-five degrees. This second scale is used for laying out roof pitches and it is evident that pitches such as one to eight, two to eight and so on may be laid out by setting the blades from this scale. On the reverse side of the protractor is furnished a third scale which is divided into twelfths so that a pitch in inches to a foot may be laid out by the use of said scale.

The blades are amber blades, that is, preferably transparent and are intended to be used in connection with a T-square or straight edge and are reversible so that the outer edge of either one of the blades may be laid against the T-square while a line is drawn along the edge of the other blade.

The protractor will be found very useful in the work of architects, engineers, builders and draftsmen and is intended to replace altogether the ordinary triangles. When the edges of the blades are set at sixty degrees with relation to each other, the instrument may be used for drawing equilateral triangles of practically any size and without the use of any other instrument. Ordinarily, the blades contact along their entire surfaces with the paper or tracing cloth on which the work is being done, and in order to facilitate lettering, an adapter is provided to be attached to one of the edges so that the blade carrying the adapter will be raised from the surface of the paper or tracing cloth and prevent the smearing of ink when the protractor is passing along a straight edge or T-square.

The protractor is provided with reinforcing hinge plates and a clamping screw for securing the blades in adjusted position. This means that the protractor has always to be used on one side and cannot be inverted but this is not necessary, as has already been stated, as either one of the blades can be laid against the T-square or even the points of the blades placed against the same which is particularly the case when let-

tering is to be done as the two blades then stand in the same angular relation with the base line or T-square.

In the accompanying drawings, one embodiment of the invention is illustrated, and—

Figure 1 is a top plan view of the protractor folded and with the adapter in position;

Figure 2 is a side elevation of Figure 1;

Figure 3 is a fragmentary bottom plan view of Figure 1;

Figure 4 shows the protractor set at right angles;

Figures 5, 6 and 7 indicate other angular settings of the instrument;

Figures 8 and 9 are fragmentary plan views of the hinge ends of the two blades;

Figure 10 is a plan view of one of the reinforcing plates with index points;

Figure 11 is a similar view of the other of the reinforcing plates, with scales for the index points; and

Figure 12 is an enlarged fragmentary section taken along line 12-12 of Figure 1.

In the drawings, reference numeral 15 represents the upper blade of the protractor as seen in Figure 1 and reference numeral 16 represents the lower blade thereof. The inner and outer edges of the blades are parallel and the ends are preferably cut off at a forty-five degree angle, as seen at 17 and 18. The center 28, Figure 9, of the hinge is situated at the intersection of the continuation of the inner edge 19 with the continuation of the inclined edge 33 of the blade 15. Concentric with this center is provided a circular projection 20 on the blade 15 which fits snugly in a concave recess 21 in the blade 16 so that the circular edges of the projection 20 and the recess 21 always contact in whatever position the blades stand to each other.

Reference numeral 22, Figure 11, indicates a reinforcing hinge plate preferably stamped out of sheet metal. This is secured on the lower blade 16 by means of screws or the like engaging in suitable apertures 23. The hinge plate has a straight edge 24 coinciding with the inner edge 19 of the blade 16 and another edge 25 coinciding with the inclined edge 18 of the same blade. The plate has a circular projection 26 having its edge concentric to a center 27 situated at the in-

tersection of the continuations of the edges 24 and 25 and when assembled the center 27 coincides with the centers 28 and 29 of the blades 15 and 16. From the edge 24 a 5 degree scale 30 ranging from zero to ninety degrees is laid out along the circular edge of the hinge plate 22 and a second scale 31 marked in eighths of a forty-five degree angle is laid out along the same edge on the 10 opposite side of the projection 26. On the reverse side of the same projection 26 is laid out the third scale 32 along the circular edge commencing at the forty-five degree edge 33 of the blade 15 when closed. This scale has 15 twelve divisions so spaced that by adjustment of the blade 16 to bring its edge 18 into registration therewith, a rise, in inches, per foot may be determined or drawn.

The plate 22 has a raised central portion 20 56 circular in contour. In the space between this raised portion 56 and the circular projection 20 of the blade 15 is inserted a stud 34, the foot portion 57 of which is secured by screws or the like to the projection 20, 25 as best seen in Figure 12. The stud projects upwardly through an opening at the center 27 in the raised portion 56 of the plate 22 and its upper threaded end engages with a thumb nut 36. Between the thumb nut 36 30 and the raised portion 56 is inserted a washer 35. It is evident that by tightening the thumb nut 36 on the stud 34 the two blades will be firmly clamped together in whatever position they are adjusted.

35 On the upper blade 15 is secured an index plate 37 by means of screws 38. This plate is arcuate to coincide with the circular edge 26 of the hinge plate 22 and its straight edge 39 coincides with the inner edge 19 of the said blade 15 while the straight edge 55 coincides with the forty-five degree edge 33 of the same blade. In continuation of these edges are formed index points 40 and 41, respectively, which 40 reach part-way over the scales 30 and 31 on the hinge plate 22.

In Figures 1, 2 and 4 is shown an adapter 42 which has two arms 43 which are bent so as to grip both top and bottom sides of one 50 of the blades. On the under side of the adapter are furnished knobbed feet 44 to permit easy sliding of the adapter on the tracing cloth or paper upon which work is being done. On the upper side of the 55 adapter is formed a raised portion 45 with a central recess 46 to facilitate the manipulation of the adapter and to provide a hold for the operator's finger.

In Figures 4 to 7 are indicated a few of 60 the positions in which the protractor can be used and reference numeral 48 represents a base line or the edge of a T-square against which different angles are intended to be drawn. When the protractor is fully open, 65 as seen in Figure 4, the two blades are set at

right angles to each other so that the line drawn against the edge 49 will be perpendicular to the base line 48.

In Figure 5, the blades are set at forty-five degrees to each other in accordance with the 70 degree scale on the protractor and a line drawn along the edge 50 will accordingly run at forty-five degrees against the base line 48. It is evident that by reversing the protractor, placing the edge 50 against the 75 base line, a line may be drawn along the outer edge of the other blade in opposite direction to the first line, but at the same angle against the base line 48.

In Figure 6 is shown a position of the protractor suitable for lettering and the blades may then be adjusted to any desired inclination of the letters, the outer edges of both 80 blades being used for this purpose. It is evident that the protractor may be set with 85 its short points near the hinge against the base line 48 or reversed and set upon the other points at the opposite ends of the blades against the base line. In the latter case, and if adjusted to a sixty degree angle 90 between the edges, the protractor may be used for laying out any size of equilateral triangles.

Instead of using the degree scale in adjusting the protractor for laying equilateral 95 triangles, the blades may be swung until the single radial line 50 on the reverse side of the plate as seen in Figure 3 registers with the edge 33.

In lettering a drawing it is advisable to use the adapter 42 on one or both of the blades 15 and 16. After setting the blades to the required angle against each other and further using the protractor as indicated in Figure 4 with the outer edge of one blade 100 against the base line 48 or stood on the points of the blades as shown in Figure 6, the protractor may then be made to slide 105 over the surface of the drawing with the feet 44 of the adapter contacting therewith 110 and the blade raised above the surface of the drawing so that if ink is used for lettering there will be no danger of smearing the same.

In Figure 7 is illustrated the use of the 115 scale 32 for inclinations of one, two, three or more inches to the foot. This setting of the protractor may be used for laying out left hand or right hand inclinations by sliding one or the other of the blades against the 120 base line. This figure also represents a setting by the use of the scale 31 for obtaining roof pitches.

Having thus described the invention, what 125 is claimed as new is:

1. A protractor comprising a pair of blades having straight edges, one of said blades, at one end, having a recess having an arcuate wall, the other blade, at the corresponding end, having a circular extension 130

rotatably fitting in the recess, a pivot carried by the said extension and concentric to the edge thereof, a plate secured to the first mentioned blade and having a portion extending over the recess therein and provided with an opening receiving the said pivot, said portion of the plate having an arcuate margin concentric to the pivot and bearing a protractor scale, and a plate secured to 5 the other blade and having an arcuate concave edge embracing the said margin of the first mentioned plate and provided with a pointer for coaction with the said scale.

2. A protractor comprising a pair of 15 blades having straight edges, one of said blades, at one end thereof, having a recess having an arcuate wall, the other blade, at the corresponding end, having a circular extension rotatably fitting in the recess, the 20 blades at their said ends having their end

edges at forty-five degrees to their straight edges, a plate secured to the first mentioned blade and having a circular portion extending over the recess therein, means pivotally connecting the circular portion of the plate 25 and the extension of the second mentioned blade, concentrically, the said extended portion of the said plate having an arcuate margin concentric to the pivot and bearing a protractor scale, the said extended portion 30 of the said plate upon its under side having a scale for registration with the said end edge of the first mentioned blade, and a plate secured to the second mentioned blade and having an arcuate concave edge embracing 35 the said margin of the first mentioned plate and provided with a pointer for coaction with the first mentioned scale thereon.

In testimony whereof I affix my signature.

HARRY H. HISTAND. [L. s.]
